EUGÈNE SCHNEIDER, OF PARIS, FRANCE, ASSIGNOR TO SCHNEIDER & CIE., OF PARIS, FRANCE, A LIMITED JOINT-STOCK COMPANY OF FRANCE.

PERCUSSION-FUSE FOR PROJECTILES.

1,352,544.

Specification of Letters Patent. Patented Sept. 14, 1920.

Application filed March 31, 1919, Serial No. 286,489. Renewed July 21, 1920. Serial No. 398,031.

To all whom it may concern:

Be it known that I, EUGÈNE SCHNEIDER, citizen of the French Republic, and a resident of 42 Rue d'Anjou, Paris, France, have 5 invented new and useful Improved Percussion-Fuses for Projectiles, which invention is fully set forth in the following specification.

This invention has for its object to provide 10 an improved percussion fuse for projectiles.

The improved fuse is characterized essentially by an apparatus that prevents premature firing, for which purpose the 15 firing mechanism is cocked by the moving apart of the striker and the percussion cap. This moving apart is effected under the action of a spring whose tension can be so adjusted that it shall be able to expand, in 20 view of the cocking of the striker, only from the instant when the counteraction of the resistance offered by the air to the progress of the projectile, has become sufficiently reduced, which will take place only at a point 25 of the trajectory at which the cocking can take place without inconvenience.

In other words, according to this invention, a recoil movement of determined extent, has to be performed by the striker before 30 it can make an entering or return movement capable of causing the firing. For this purpose segments that constitute a shoulder for the striker and prevent the latter from moving toward the percussion cap, are in 35 their turn prevented from moving out of the way because they are held by being situated between the fuse body and the striker body so long as the striker has not made the desired recoil movement.

40 Two constructional forms of this invention are illustrated by way of example in the accompanying drawings in which:—

Figures 1 to 8 illustrate a first constructional form.

45 Fig. 1 is a longitudinal axial section of the fuse in the position of rest.

Figs. 2, 3 and 4 are similar sections showing the parts in the positions they occupy during the travel of the projectile, respectively in the gun barrel, at an intermediate

point of the trajectory, and on impact against the target.

Figs. 5 and 6 are cross sections respectively on the lines V—V and VI—VI of Fig. 1.

55 Fig. 7 is a cross section on the line VII—VII of Fig. 2.

Fig. 8 is a section of the safety ring on the line VIII—VIII of Fig. 5.

Figs. 9 to 14 illustrate a second constructional example of the invention.

Fig. 9 is a partial longitudinal section of the fuse on the line IX—IX of Fig. 14, in the state of rest.

60 Figs. 10 to 13 inclusive are sections similar to Fig. 9, showing the parts of the fuse in various positions of operation.

Fig. 14 is a cross section on the line XIV—XIV of Fig. 9.

65 Referring more particularly to Figs. 1 to 8, A is a fuse body containing in its rear end a fixed percussion cap carrier B of any known construction. C is the striker guided in the fuse body. All movement of the striker toward the percussion cap carrier is 70 impossible so long as the striker has not made a recoil movement of a determined extent for the purpose of becoming cocked.

To this end the striker bears against segments F by means of a shoulder E which, in 75 this first constructional example, is formed on a sleeve D that is guided on the fuse body. These segments are held normally in place in a groove a in the fuse body A by the free edge of the sleeve D.

80 The amount of the recoil movement which is to be made by the striker in order to release the segments F and allow them to escape by centrifugal action, is determined by the height H of the edge of the sleeve that 85 covers the said segments.

85 While at rest (Fig. 1) all forward movement of the striker toward the percussion cap is prevented by the segments F against which the striker bears. All movement of the striker away from the percussion cap is 90 prevented by bolts I which are movable in guides a¹ formed in the body A and are held in place by the engagement of a neck i in a notch j in a safety ring or annular slide J. 100

This ring is held, while at rest, in its locking position by a spring G bearing at one end under the lower end of the said ring, and bearing at its other end upon the fixed per-
5 cushion cap carrier B.

The lower or rear portion of reduced internal diameter, of the ring J in the state of rest (Figs. 1, 5 and 6) thus keeps clamped in a reduced portion C¹ of the stem of the
10 striker, two flexible blades K which have a constant tendency to open outward.

On the shot being fired, the annular slide or ring J having a suitably determined mass for this purpose, remains behind owing
15 to its inertia and thus compresses the spring G, assuming the position shown in Fig. 2. In this movement, as soon as the portion of reduced internal diameter of the ring J has moved beyond the lower edge of the
20 blades K the latter open and enter the portion of largest diameter of the ring (Figs. 2 and 7), while being retained in the reduced portion C¹ of the stem of the striker.

The parts retain this position during the
25 entire duration of the acceleration; the segments F remaining confined in groove a of the fuse body between the latter and the sleeve D that is fixed to the striker.

When the acceleration has ceased, and the
30 diminution in the resistance to the advance of the projectile has allowed the spring G to overcome this resistance and to expand, the ring J is forced forward. As soon as the shoulder j¹ of this ring meets the blades
35 K, it carries by means of the latter, the striker C and the sleeve D along with it.

The cocking of the striker, that is to say, the possibility of the striker moving toward the percussion cap, is effected only at the
40 instant when the striker being forced toward the rear, has thus made a recoil movement through the distance H which is sufficient to uncover the segments F and allow them to be driven outward by centrifugal
45 action (Fig. 3).

In the example shown in Figs. 9 to
14 the segments for holding back the striker have a portion F of larger diameter which is held when at rest, between a shoulder
50 E of the body of the striker and the forward end A¹ of the fuse body A, by reason of a portion F¹ of reduced diameter of the said segments becoming engaged between the fuse body and a reduced portion C² of
55 the body of the striker.

While at rest, the recoil of the striker is prevented by the safety ring or annular slide J bearing against the spring G and a means of locking the said ring. This locking means comprises a counter-ring M whose internal diameter is equal to that of the body of the striker C and the rear reduced inner portion of the ring J. The rear portion of the counter-ring engages in the

forward portion of larger diameter of the 65 ring J. Two recesses in the counter-ring receive two bolts I of segment-shape which, when at rest, are kept pressing against a reduced portion C³ of the body of the striker by a spring I¹ that is arranged in a groove 70 in the said bolts and in a groove m in the counter-ring M.

On the shot being fired the annular slide or ring J remains behind by reason of its own inertia, and the counter-ring M tends 75 to force back the bolts I. These however are held in the reduced portion C³ of the body of the striker until the forward end of the ring J has moved past their rear edges and has allowed them to move slightly 80 apart and be forced by the thrust of the counter-ring M, away from the chamfer c, as shown in Fig. 10.

As soon as the counter-ring M and the bolts I have come opposite the reduced portion C¹, the spring I² will move the bolts I toward each other, and the combination M—I—I—J will assume as a whole the position shown in Fig. 11, which said position it will retain to the end of the acceleration 90 and up to the instant when the resistance to the advance of the projectile will have become sufficiently diminished to allow the action of the spring G to predominate. This said action causes the striker to recoil for 95 the purpose of being cocked. This cocking can only take place, and the striker can move toward the percussion cap only after the segments F have been ejected which requires that the recoil shall be equal to 100 the distance H that is determined by the height of the portion F¹ of the said segments. The recoil is produced by the striker being carried along as soon as the combination J—I—M has recoiled in its turn as a 105 whole to the point where the segments I come against the chamfer c¹.

Fig. 12 shows the parts of the fuse in the cocked position of the striker.

Fig. 13 shows the same parts in the position they occupy when the projectile has struck the target.

In the hereinbefore described examples, the moving apart of the striker and the percussion cap, which is necessary for cocking 115 the firing mechanism is assumed to be effected by an apparatus comprising a movable striker and a stationary percussion cap carrier.

It is however to be understood that the 120 reverse arrangement may be adopted for the two elements of the said apparatus; that is to say, the striker may be stationary and the percussion cap carrier may be movable.

What I claim is:—

1. A percussion fuse comprising a body-part having an axial bore with a cap-carrier at the inner end of said bore, a striker mov-

able in the axial bore having a head projecting beyond the body-part operating on impact to drive the striker inward onto the cap-carrier, a spring normally pressing the 5 striker outward, centrifugally actuated bolts slideable in the body-part to engage the striker to hold the latter inward against the outward thrust of the spring, said bolts moving outwardly to release the striker in response to the centrifugal force imparted by the rotation of the discharged projectile, 10 and displaceable segments interposed between the body-part and an element of the striker to limit the inward movement of the 15 striker toward the cap-carrier, said segments being freed by the forward movement of the released striker imparted by the spring, the freed segments responding to the centrifugal force imparted by the rotation of the discharged projectile to move 20 clear of the striker to permit subsequent inward movement of the latter onto the cap-carrier.

2. A percussion fuse comprising a body-part having an axial bore with a cap-carrier at the inner end of said bore, a striker movable in the axial bore having a head projecting beyond the body-part operating on impact to drive the striker inward onto the 25 cap-carrier, a spring normally pressing the striker outward, centrifugally actuated bolts slideable in the body-part to engage the striker to hold the latter inward against the outward thrust of the spring, said bolts moving outwardly to release the striker in response to the centrifugal force imparted by the rotation of the discharged projectile, 30 an annular slide movable on the striker in said axial bore to engage the bolts to hold them in engagement with the striker, said slide operating through its inertia at the discharge of the projectile to move inward in the bore to free the bolts to respond to the centrifugal force imparted by the rotation of the projectile, and displaceable segments interposed between the body-part and an element of the striker to limit the inward movement of the striker toward the cap-carrier, said segments being freed by the forward movement of the released striker imparted by the spring, the freed segments responding to 35 the centrifugal force imparted by the rotation of the discharged projectile to move clear of the striker to permit subsequent inward movement of the latter onto the cap-carrier. 40

4. A percussion fuse comprising a body-part having an axial bore with a cap-carrier at the inner end of said bore, a striker movable in the axial bore having a head projecting beyond the body-part operating on impact to drive the striker inward onto the cap-carrier, a spring normally pressing the striker outward, centrifugally actuated bolts slideable in the body-part to engage the striker to hold the latter inward against the outward thrust of the spring, said bolts moving outwardly to release the striker in response to the centrifugal force imparted by the rotation of the discharged projectile, 45 an annular slide movable on the striker in said axial bore and pressed outwardly by said spring to engage the bolts to hold the latter in engagement with the striker, spring blades between the annular slide and the striker, said annular slide operating through its inertia at the discharge of the projectile to move inward to compress the spring and to free the bolts to respond to the centrifugal force imparted by the rotation of the projectile, said spring after overcoming the 50 inertia of the annular slide operating to press outwardly said slide, the latter in its outward movement engaging the lower ends of the spring blades, which are in engagement at their upper ends with the striker, to force outwardly said striker to project the head of the latter beyond the body-part, and displaceable segments interposed between 55 the body-part and an element of the striker to limit the inward movement of the striker toward the cap-carrier.

3. A percussion fuse comprising a body-part having an axial bore with a cap-carrier at the inner end of said bore, a striker movable in the axial bore having a head projecting beyond the body-part operating on impact to drive the striker inward onto the cap-carrier, a spring normally pressing the striker outward, centrifugally actuated bolts

slidable in the body-part to engage the striker to hold the latter inward against the outward thrust of the spring, said bolts moving outwardly to release the striker in response to the centrifugal force imparted by the rotation of the discharged projectile, 65 an annular slide movable on the striker in said axial bore and pressed outwardly by said spring to engage the bolts to hold the latter in engagement with the striker, said annular slide operating through its inertia at the discharge of the projectile to move inward to compress the spring and to free the bolts to respond to the centrifugal force imparted by the rotation of the projectile, 70 said spring after overcoming the inertia of the annular slide operating to press outwardly said slide together with the striker to project the head of the latter beyond the body-part, and displaceable segments interposed between the body-part and an element of the striker to limit the inward movement of the striker toward the cap-carrier, said segments being freed by the forward movement of the released striker imparted by the spring, the freed segments responding to 75 the centrifugal force imparted by the rotation of the discharged projectile to move clear of the striker to permit subsequent inward movement of the latter onto the cap-carrier. 80

4. A percussion fuse comprising a body-part having an axial bore with a cap-carrier at the inner end of said bore, a striker movable in the axial bore having a head projecting beyond the body-part operating on impact to drive the striker inward onto the cap-carrier, a spring normally pressing the striker outward, centrifugally actuated bolts slideable in the body-part to engage the striker to hold the latter inward against the outward thrust of the spring, said bolts moving outwardly to release the striker in response to the centrifugal force imparted by the rotation of the discharged projectile, 85 an annular slide movable on the striker in said axial bore and pressed outwardly by said spring to engage the bolts to hold the latter in engagement with the striker, spring blades between the annular slide and the striker, said annular slide operating through its inertia at the discharge of the projectile to move inward to compress the spring and to free the bolts to respond to the centrifugal force imparted by the rotation of the projectile, said spring after overcoming the 90 inertia of the annular slide operating to press outwardly said slide, the latter in its outward movement engaging the lower ends of the spring blades, which are in engagement at their upper ends with the striker, to force outwardly said striker to project the head of the latter beyond the body-part, and displaceable segments interposed between 95 the body-part and an element of the striker to limit the inward movement of the striker toward the cap-carrier.

the body-part and an element of the striker to limit the inward movement of the striker toward the cap-carrier, said segments being freed by the forward movement of the released striker imparted by the spring, the freed segments responding to the centrifugal force imparted by the rotation of the discharged projectile to move clear of the striker to permit subsequent inward movement of the latter onto the cap-carrier.

5. A percussion fuse comprising a body-part having an axial bore with a cap-carrier at the inner end of said bore, a striker movable in the axial bore having a head projecting beyond the body-part operating on impact to drive the striker inward onto the cap-carrier, a spring normally pressing the striker outward, centrifugally actuated bolts 15
20
25
30
35
slidable in the body-part to engage the striker to hold the latter inward against the outward thrust of the spring, said bolts moving outwardly to release the striker in response to the centrifugal force imparted by the rotation of the discharged projectile, a sleeve fixed to the forward end of the striker and extending over the body-part, and displaceable segments seated in a groove in the body-part and abutting a shoulder on the overlapping sleeve to limit the inward movement of the striker toward the cap-carrier, said segments being freed on the outward movement of the sleeve when so carried by the striker, the freed segments being displaced by centrifugal force imparted by the rotation of the projectile to permit subsequent inward movement of the striker onto the cap-carrier.

6. A percussion fuse comprising a body-

part having an axial bore with a cap-carrier at the rear end of said bore, a striker 40 having a shank movable in said axial bore and provided with an impact head, displaceable segments interposed between an element of the fuse body-part and an element of the striker to prevent premature rearward movement of the striker toward the cap-carrier, locking mechanism including 45
50
55
60
65
70
bolts to engage the striker-shank to hold the striker at the limit of its rearward movement to which it is restricted by the interposed segments, an annular slide slidable on the striker-shank operating in its initial forward position to hold the bolts in locked engagement with the striker-shank, a cocking spring normally pressing the annular slide forward, said annular slide at the discharge of the projectile moving rearward by its inertia against the action of the cocking spring to free the bolts to be actuated to release the striker-shank, said cocking spring during the flight of the projectile and the lessening acceleration thereof predominating the inertia of the annular slide to move the latter forward, and means for imparting the forward movement of the annular slide to the striker-shank to move the striker forward to cocked position, the forward movement of the striker releasing the segments to be displaced by centrifugal action imparted by the rotation of the projectile to permit rearward movement of the striker onto the cap-carrier when the impact head strikes a target.

In testimony whereof I have signed this specification.

EUGÈNE SCHNEIDER.
